UNITED STATES PATENT OFFICE.

BENJAMIN S. BOWERS, OF LA PRAIRIE, MINNESOTA.

ADVERTISING TOY.

1,203,967.

Specification of Letters Patent. Patented Nov. 7, 1916.

Application filed May 17, 1916. Serial No. 98,126.

To all whom it may concern:

Be it known that I, BENJAMIN S. BOWERS, a citizen of the United States, residing at La Prairie, in the county of Itasca, State of Minnesota, have invented a new and useful 5 Advertising Toy; and I do hereby declare the following to be a full, clear, and exact description of the invention, such as will enable others skilled in the art to which it 10 appertains to make and use the same.

This invention relates to a new and useful advertising toy, and an object of the invention is to provide an improved, simple, efficient and practical toy of this kind, which 15 creates a noise, when blowing the same, and when blown, the air passing therethrough fills a paper bag (which may be provided with interior and exterior advertisements) attached to one end of the toy, subsequently 20 to which the bag may be bursted, thereby creating a loud report.

In practical fields the details of construction may necessitate alterations, falling within the scope of what is claimed.

25 The invention comprises further features and combination of parts, as hereinafter set forth, shown in the drawings, and claimed.

In the drawings:—Figure 1 is a view in perspective of the improved toy constructed in accordance with the invention. Fig. 2 is a longitudinal sectional view through the same on line 2—2 of Fig. 1. Fig. 3 is a sectional view on line 3—3 of Fig. 2.

Referring more especially to the drawings 30 1 designates a tubular member, one end of which is provided with a conical enlargement 2, which tapers toward the body of the tubular member. Secured in a depression 3 of the conical enlargement by means 35 of the pin 4 is a shell 5, having a valve opening 6 at one end and being opened at the other end as at 7. A spring tensioned valve 8 coöperates with the valve opening 6, so as to check or retain the air, that may be 40 blown into the paper bag 9, which is secured or clamped to the conical enlargement by the disk ring 10, which is wedged on the conical enlargement at diametrically opposite points thereof. It will be noted that 45 the larger end of the conical portion ex-

tends into the bag. A suitable tone reed, designated as a whole by the numeral 11, is fitted into the end of the tubular member 1, opposite the conical enlargement. This tone reed comprises the tubular member 12 having the shoulder 13 (which engages the smaller end of the tubular member 1 to limit the insertion of the part 12) and the vibrating tone blade 14, which is secured at 15 in any suitable manner to the tubular 60 part 12, and lies substantially across the passage at one end of the member 12.

It is the object of this invention that the exterior surfaces of bags should be provided with advertisements, and advertising circulars on the interior of the bag, as shown at 18 in Fig. 2, and such toys to be given away by grocery stores, shoe stores, and department stores and the like, so as to advertise such firms and articles sold thereby, and 65 at the same time create amusement for the children.

To use the toy, it is the object to blow through the tubular member 1, thereby making a noise with the reed 11, the air automatically opening the check valve, and entering the bag. After the bag is filled with air, operator grasps the tubular member 1 close to the disk ring 10, whereby the other end of the bag may be mashed toward the 80 conical enlargement, bursting the same, which will cause a loud report, owing to the air suddenly escaping subsequently to the sudden compression of the air.

The invention having been set forth what 85 is claimed as new and useful is:—

1. In an article of manufacture, the combination of a tubular member having a check valve in one end and a tone reed secured in the opposite end, of a paper bag detachably clamped to the end having the check valve, whereby as air passes through the tubular member, the tone reed creates a noise and the bag is filled with air, which bag 90 may be subsequently bursted. 95

2. In an article of manufacture, the combination of a tubular member having a conical enlargement at one end and a tone reed secured in the opposite end, of a check valve in the conical enlargement, a bag, through 100

the open end of which the conical enlargement is inserted, a disk ring to clamp the sides of the open end of the bag on the conical enlargement, whereby as air is blown through the tubular member the tone reed creates a noise and fills the bag which may be subsequently bursted.

In testimony whereof I have signed my name to this specification in the presence of two subscribing witnesses.

BENJAMIN S. BOWERS.
